UNITED STATES PATENT OFFICE.

JOHN M. ALEXANDER, OF TIMBERVILLE, VIRGINIA.

AUTOMATIC CAR-COUPING.

1,201,422.

Specification of Letters Patent. Patented Oct. 17, 1916.

Application filed June 11, 1914. Serial No. 844,537.

To all whom it may concern:

Be it known that I, JOHN M. ALEXANDER, a citizen of the United States, residing at Timberville, in the county of Rockingham and State of Virginia, have invented a new and useful Automatic Car-Coupling, of which the following is a specification.

The invention relates to improvements in car couplings.

10 The object of the present invention is to improve the construction of car couplings and to provide a simple, practical, and comparatively inexpensive car coupling of the Janney type, equipped with means adapted, 15 in the operation of coupling, to be actuated by an approaching car coupling, and capable of unlocking the pivoted knuckle and of opening the same, whereby such knuckle is automatically arranged in proper position 20 for coupling, without necessitating a train hand going between the cars and opening or otherwise positioning the knuckle by hand.

25 A further object of the invention is to provide a car coupling of this character in which the automatic coupling actuated elements of the automatic knuckle opening means will lie beyond the interlocked portions of the car couplings when the same are 30 coupled, so that there will be no liability of the coupling actuated elements being accidentally operated or injured through the relative movement of the knuckles when the cars are in motion.

35 It is also an object of the invention to provide an automatic knuckle opening device which, in event of any of its parts being broken or otherwise injured, will not impair the action of the car coupling in its ordinary operations of coupling and uncoupling, so that injury to the automatic device will not necessitate any repair to the car coupling while on the road.

40 With these and other objects in view the invention consists in the construction and novel combination of parts hereinafter fully described, illustrated in the accompanying drawings, and pointed out in the claims hereto appended, it being understood that 45 various changes in the form, proportion, size and minor details of construction, within the scope of the claims, may be resorted to without departing from the spirit or sacrificing any of the advantages of the 50 invention.

55 In the drawings: Figure 1 is a view, partly

in plan and partly in horizontal section, of two car couplings constructed in accordance with this invention, and shown coupled. Fig. 2 is a similar view, the coupling actuated lever being moved inwardly a sufficient distance to operate the locking device and release the knuckle. Fig. 3 is a view similar to Fig. 2, the coupling actuated lever being moved to the limit of its inward movement 60 and the knuckle being completely open. Fig. 4 is a transverse sectional view on the line 4—4 of Fig. 1. Fig. 5 is a transverse sectional view on the line 5—5 of Fig. 1. Fig. 6 is a longitudinal sectional view on the line 6—6 of Fig. 2. Fig. 7 is a detail perspective view of the coupling actuated lever. Fig. 8 is a detail perspective view of the pivoted locking device. Fig. 9 is a detail horizontal sectional view on the line 9—9 of Fig. 75 6. Fig. 10 is a transverse sectional view on the line 10—10 of Fig. 6. Fig. 11 is a detail longitudinal sectional view on the line 11—11 of Fig. 1. Fig. 12 is a detail perspective view of the laterally movable knuckle 80 opening link or member. Fig. 13 is a detail perspective view of the knuckle.

Like numerals of reference designate corresponding parts in all the figures of the drawings.

85 In the accompanying drawings, in which is illustrated the preferred embodiment of the invention, 1 designates a coupler head having an integral guard arm 2 at one side and provided at the other side with an integral knuckle supporting portion or arm 3 having spaced upper and lower ears 4 for the reception of a pin 5 for pivoting a knuckle 6 to the coupler head. The knuckle 6^a of a companion or complementary car 90 coupling is arranged between the inner portion 7 of the guard arm and the knuckle supporting portion or arm when the car couplings are coupled, as illustrated in Fig. 1 of the drawings. The knuckle 6 is locked in its 95 closed position by a locking device 8 pivoted at its rear end within the coupler head and extending longitudinally thereof and adapted to be swung upwardly above the arm 9 of the knuckle to release the same. The locking device 8 is preferably provided at its 100 rear end with laterally projecting integral pivot studs 10, which are arranged in bearings 11 and 12 of the coupler head. The bearing 11 is open at its front to enable the 105 locking device to be placed in the bearings, and after the parts are assembled, the 110

knuckle will prevent any displacement of the locking device. The arm of the knuckle is preferably provided with a laterally projecting integral lug 13, adapted to engage 5 with a shoulder 13^a of the adjacent side of the coupler head to prevent the knuckle from pulling out in event of the breakage of the knuckle pin.

In order to obviate the necessity of opening 10 the knuckle by hand to arrange the same in proper position for automatical coupling, the car coupling is equipped with an automatic knuckle unlocking and opening device comprising a coupling actuated lever 14 and 15 a laterally movable link 15. The lever 14, which is arranged in a longitudinal opening 16 in the guard arm of the coupler head, consists of a curved body portion tapered inwardly and rearwardly, as clearly shown in 20 Fig. 7 of the drawings, and provided at its front or outer end with a laterally extended head 17, which projects forwardly or outwardly at an extension 18 of the guard arm 2. The extension 18, which lies beyond the 25 inner knuckle confining portion 7 of the guard arm, has a front concave face, and the opening 16 extends inwardly or rearwardly from the said concave face of the extension 18. The laterally projecting portion of the 30 head 17 is slightly rounded at the rear side at 19, which is arranged in a vertical bearing recess 20 in the outer wall of the longitudinal opening 16. The knuckle formed by the laterally extended head 17 projects 35 through the opening in the front face of the extension of the guard arm and is adapted to be engaged by an approaching car coupling, whereby when the two car couplings come together, the lever 14 will be 40 moved inwardly to swing the locking device upwardly and then swing the knuckle outwardly to open the latter.

The inner end 21 of the lever 14 extends into a recess 22 in the locking device 8, and 45 it has its rear wall 23 beveled and presenting an inclined face to the rear wall 24 of the recess 22. The rear wall 24 is correspondingly inclined and the first portion of the inward swinging movement of the lever 14 50 carries the inclined face 23 thereof into engagement with the rear inclined wall of the locking device and lifts the latter out of engagement with the arm of the knuckle. This operation is effected prior to swinging the 55 knuckle. The inner end 21 of the lever is provided in its lower face with a cylindrical bearing recess or socket 25 for the reception of a pivot stud 26, extending upwardly from one end of the link 15. The link slides transversely of the coupler head in a substantially 60 diagonally arranged groove 27, which is deepened at 28 to enable the link to be tilted to introduce its pivot stud 26 into the bearing recess 25 and to remove it therefrom. 65 This operation is possible when the knuckle

is detached. As an enlarged end 29 of the link extends beneath the arm of the knuckle when the parts are assembled, the knuckle will maintain the link in a horizontal position and prevent the same from becoming 70 accidentally disconnected from the lever 14. The link 15 is provided adjacent to its enlarged end 29 with a pivot stud 30, adapted to be carried into a recess 31 of the arm of the knuckle by the inward movement of the 75 lever 14, so that the continued inward movement of the lever will operate to move the link laterally of the draw head and swing the knuckle on its pivot to open the latter. The recess in the arm of the knuckle and the 80 recess or space 32 in the adjacent wall of the coupler head provide ample space for a limited movement of the link independently of the knuckle. The knuckle, in its closing movement, engages the pivot stud 30 and 85 moves the link 15 inwardly and swings the lever 14 outwardly. If the movement of the knuckle is not quite sufficient to return the lever to its initial position, such movement of the lever and the link will be completed 90 by the knuckle of the companion coupling head engaging the enlarged inner end 29 of the link. The enlarged inner end 29 of the link is approximately L-shaped, and projects 95 into the space between the knuckle supporting arm or portion and the guard arm when the lever is moved inward.

In order to enable the knuckle to be unlocked and opened manually, the car coupling is equipped with a rock shaft 33 mounted in a slot 34 of the locking device and provided at one side thereof with a forwardly extending substantially L-shaped arm 35, extending over and arranged to engage the lever 14, which is slightly rounded at 36 adjacent to its inner end 32 to cooperate with the arm 35 of the rock shaft. The rock shaft is provided at the other side of the locking device with a rearwardly extending arm 37 connected to the lower end 100 of a lifting link or rod 38 extending upwardly through an opening 39 in the top of the coupler head. The lifting link or rod, which is designed to be connected at its upper end by a chain 40 with a suitable operating device (not shown) is provided at its lower end with an eye 41, which is linked into an opening 42 in the rear end of the arm 37. When the lifting link or rod is drawn upwardly, the rock shaft is partially rotated, and the rock shaft arm 35 engages the lever 14 and swings the same inwardly or rearwardly, the slot 34, which extends longitudinally of the locking device, permitting the 105 necessary play of the parts incident to the upward movement of the locking device and the rearward or inward movement of the lever 14. The rock shaft and its arms constitute a lever which is fulcrumed against 110 the front wall of the slot to actuate the lever 115 120 125 130 135

14. The said upward movement of the rod lifts the locking device and the inward movement of the lever actuates the link 15 and opens the knuckle.

5 As the automatic device does not depend for its operation on the action of a spring or springs, and as the engaged portion of the lever 14 is located beyond the inner knuckle confining portion 7 of the guard arm, the 10 said device is not liable to become broken or get out of order, and should the automatic device become inoperative through any means, it will not affect the ordinary operations of the knuckle and the locking 15 device in coupling and uncoupling, and will not require any repairs on the road while the train is traveling between the terminal points of its run.

What is claimed is:—

20 1. A car coupling including a coupler head provided at one side with a guard arm and having a pivoted knuckle at the opposite side, a locking device for holding the knuckle in its closed position, a coupling 25 actuated lever mounted within the coupler head and having a projecting portion arranged to be engaged by a companion car coupling, said lever being also provided with means for operating the locking device, 30 and a link pivotally connected with the lever and provided with means for actuating the knuckle to open the same.

2. A car coupling including a coupler head, a knuckle pivoted thereto and provided with an arm having an open bearing or recess, a locking device for holding the knuckle in its closed position, a coupling 35 actuated lever mounted within the coupler head and having a projecting portion arranged to be engaged by a companion car coupling, said lever having means for operating the locking device to release the knuckle, and a link pivoted to the lever and provided with a projecting pivoted portion 40 arranged to engage the open bearing or recess of the knuckle for opening the latter.

3. A car coupling including a coupler head, a pivoted knuckle, a locking device for holding the knuckle in its closed position, a 50 coupling actuated lever mounted within the coupler head and having a projecting portion arranged to be engaged by a companion car coupling, said lever being also provided with means for operating the locking device 55 to release the knuckle, and a link carried by the lever and provided with means for actuating the knuckle, said link being also provided with a portion adapted to project from the coupler head in position to be engaged by the knuckle of the said companion car coupling to insure a complete return of the lever to its initial position.

4. A car coupling including a coupler

head, a pivoted knuckle, a locking device for holding the knuckle in its closed position, a 65 coupling actuated lever mounted within the coupler head and having a projecting portion arranged to be engaged by a companion car coupling, said lever being also provided with means for operating the locking device 70 to release the knuckle, means carried by the lever for opening the knuckle after the same has been released, and a manually operable device arranged to actuate the said lever.

5. A car coupling including a coupler 75 head, a pivoted knuckle, a locking device for holding the knuckle in its closed position, a coupling actuated lever mounted within the coupler head and having a projecting portion arranged to be engaged by a companion car coupling, said lever being also provided with means for operating the locking device 80 to release the knuckle, means carried by the lever for opening the knuckle after the same has been released, and a manually operable 85 device mounted on the locking device and arranged to lift the same and to actuate the said lever.

6. A car coupling including a coupler 90 head, a pivoted knuckle, a locking device for holding the knuckle in its closed position, a coupling actuated lever mounted within the coupler head and having a projecting portion arranged to be engaged by a companion car coupling, said lever being 95 also provided with means for operating the locking device to release the knuckle, means carried by the lever for opening the knuckle after the same has been released, a lever device fulcrumed on the locking device and provided with opposite arms, one of the arms being arranged to engage and actuate the said lever, and lifting means connected with the other arm of the said lever device.

100 7. A car coupling including a coupler head having a transverse groove or way provided with a depression, a pivoted knuckle, a locking device for holding the knuckle in its closed position, a coupling actuated lever mounted within the coupler head and having a bearing at its ends, a link having a projecting pivot adapted to be introduced into and removed from the bearing at the depressed portion of the groove or way, said 110 link being provided with means for actuating a knuckle and being retained in engagement with the lever by the said knuckle.

115 In testimony, that I claim the foregoing as my own, I have hereto affixed my signature in the presence of two witnesses.

JOHN M. ALEXANDER.
